UNITED STATES PATENT OFFICE.

JOHN F. STANDISH, OF WINTHROP, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WORK-HOLDING MEANS FOR SHOE-MACHINES.

1,259,796.

Specification of Letters Patent. Patented Mar. 19, 1918.

Application filed May 23, 1916. Serial No. 99,327.

To all whom it may concern:

Be it known that I, JOHN F. STANDISH, a citizen of the United States, residing at Winthrop, in the county of Suffolk and State of Massachusetts, have invented certain Improvements in Work-Holding Means for Shoe-Machines, of which the following description, in connection with the accompanying drawings, is a specification, like reference characters on the drawings indicating like parts in the several figures.

This invention relates to work holding means for shoe machines and, in the following specification and accompanying drawings, it is described and illustrated as applied to a heelng machine of the type disclosed in U. S. Patent No. 1,157,688, granted Oct. 26, 1915. It should be understood that this is merely for the purpose of making an adequate disclosure of the invention and that the invention is not limited in its utility to embodiment in this particular type of machine but that it may be advantageously used in a variety of machines for operating upon boots or shoes.

In attaching or securing together the different parts of a shoe, it is frequently necessary to adjust one or more of the parts in order that they may be brought into proper relation to each other before they are secured together. When the shoe is mounted upon a wooden last, it is also frequently necessary to adjust the shoe or last supporting member to conform to non-symmetrical or misshapen lasts. While it is desirable to be able to make these adjustments frequently and expeditiously, it is nevertheless frequently desirable, and often necessary, that the parts be held rigidly in adjusted position while the operation of attaching them together is being carried out.

The object of the present invention is to provide work holding means for shoe machines that will permit such adjustments as those above referred to, to be made easily and rapidly, and will then hold the respective parts rigidly against relative movement while they are being secured together. With this object in view an important feature of the invention consists in the provision of a freely movable work support and a freely movable work clamp in combination with means, preferably automatic, for locking the said devices rigidly against movement

after the desired adjustments have been made. In the preferred form of the invention the movements of the clamp are effected by movement of the work support so that by moving the work support or jack to the position to locate the shoe properly relatively to the part to be attached to it, for example, a heel, the clamp will automatically be located in the proper position to receive the shoe. It is, furthermore, preferred to provide separate sets of stops for independently determining the limits of movement of the work clamp and the shoe support to the end that, in their final positions, they may be made to occupy any desired relation to each other, and this result is conveniently accomplished by supporting the stops for the shoe support upon the carrier which carries the clamp.

A further feature of the invention relates to a work clamp comprising clamping members, or jaws, which are relatively movable to receive the work and to accommodate work of different sizes, in combination with means for locking the said jaws solidly against movement after the work has been introduced between them, so that the force applied in the subsequent operations upon the work cannot displace it. This result may be conveniently secured by providing a normally inoperative lock or clutch for the clamping jaws and a controlling member, such as, for example, a back stop, arranged to throw the lock into operation when the said controlling member is engaged by the work inserted into the clamp.

Further features and details of the invention will appear from the following description, taken in connection with the accompanying drawings, in which:

Figure 1 is a perspective view of an embodiment of the invention applied to a well known type of heelng machine;

Fig. 2 is a side elevation of the mechanism shown in Fig. 1, showing additional details of its mounting and relation to the remainder of the machine;

Fig. 3 is a sectional view, taken in a vertical, medial plane from front to rear;

Fig. 4 shows a detail of the adjustable stops for the work clamp;

Fig. 5 illustrates details of the locking mechanism for the work clamp; and

Fig. 6 shows, upon an enlarged scale, de-

tails of the locking mechanism for the work support.

Referring to the drawings, 10 indicates a portion of the frame of a heeling machine. 12 indicates the usual jack supporting spindle connected to the front end of the walking beam, the rear end of which is operated by the back rod 14, all as more completely disclosed in the prior patent 10 above referred to. The work support herein disclosed comprises a jack 16 pivoted at 18 to the jack slide 20, carried by the spindle 12.

In order to provide for transverse adjustment of the jack, to compensate for various degrees of asymmetry in the form or location of the last, the upper end of the jack post is transversely slotted, as shown at 22, and is mounted for free sliding movement 20 on the guide 24. The jack is separated at 26 into an upper section 28 and a lower section 30, respectively, the sections being connected by a plunger 32. The upper end of the plunger 32 carries a corrugated 25 plate 34 which is located in a recess 36 in the section 28, the size of the recess being so proportioned that a limited amount of vertical movement of the plunger 32 is permitted. Normally, the weight of the lower 30 jack section causes the plate 34 to rest in the bottom of the recess 36 but when the upward pressure is exerted on the jack the plunger 32 and plate 34 are raised until the two sections of the jack abut and the teeth 35 upon the plate 34 mesh with a corresponding series of teeth upon the lower face of a locking plate 38 rigidly mounted in the guide member 24. By virtue of this construction, the jack is freely movable for 40 transverse adjustment upon the guide 24 as long as it hangs freely pendent, but as soon as pressure is exerted upon the work by relative approaching movement of the jack and nailng die 40, the teeth upon the plates 45 34 and 38 mesh, as shown in Fig. 3, and the jack is held rigidly against movement from its adjusted position until the pressure is released.

In order to locate the shoe relatively to 50 the heel, a clamp for engaging the counter and rand crease of the shoe is provided. The slide 42 is supported for movement forwardly and rearwardly of the machine in a stationary dovetailed guide 44. An adjusting screw 46, having at its forward end a crank handle 48, is journaled in a bearing 55 forming part of the slide 42 and enters a stationary nut 52 secured to the guide casting 44. By turning the crank 48 the 60 slide 42 and the entire mechanism of the clamp, carried thereby, are adjusted bodily forwardly or rearwardly. The clamp and its connections to the slide 42 will now be described:

In the front end of the slide 42 are secured track bars 54, 56. A casting 58 carries rollers 60 and 62 which travel, respectively, upon the bars 54, 56, permitting the casting 58 to be moved in a right line transversely of the machine. A projection 64, 70 secured to the rear face of the casting 58, is located between a pair of stops 66, 68 which are adjustable toward and from each other by means of a right and left screw 70 having at one end a crank and handle 72. 75 A spring pressed pin 74 in the handle 72 is arranged to enter a hole 76 in the slide 42. By pulling out the pin 74, the crank and the screw may be turned an integral number of revolutions and will be held in adjusted 80 position by again allowing the pin to enter the hole. The purpose of limiting the adjustment to an integral number of revolutions of the screw will become apparent later. A slide 78 is mounted for free vertical movement in dove-tailed guides in the casting 58 and is supported by a chain 80 which passes over an idle sprocket 82 and is connected to a hook 84 projecting rearwardly from the jack post hanger 86. By 85 inserting the hook 84 in different links of the chain 80, vertical adjustment of the slide 78 is secured and, by means of the connections described, the slide is raised and lowered as the jack is swung outwardly and 90 inwardly. This detail of construction is similar to machines already known in the 95 art.

A clamp head 88 is secured by clamping screws 90 to a stud 92 supported in the 100 slide 78. By loosening the screws 90, pivotal adjustment of the head and the clamp carried thereby in a vertical plane is permitted. This is for the purpose of causing the clamping jaws to enter properly the 105 rand creases of shoes having heels of different height and pitch. A pair of clamping arms 94, 96 are mounted upon the head 88 for pivotal movement in a horizontal plane, and carry at their front ends jaws 110 98 for engaging the counter and rand crease of a shoe. A pair of links 100 connects the rear ends of the clamping bars together and the links in turn are pivotally connected by a center pin 102 which is mounted in a 115 slide 104 mounted for movement forwardly and rearwardly in guides 106 formed in the head 88. A spring 108 is connected to the slide 104 and tends to draw the slide rearwardly, spreading the rear ends of the arms 120 and forcing the jaws 98 toward each other. The spreading movement of the rear ends of the arms and, consequently, the approaching movement of the jaws are limited by a rod 110 threaded into an adjustable thumb nut 112. The clamping arms are adjusted until the spacing between the jaws 98 is 125 slightly less than the width of the shoe,

the spring 108 permitting the jaws to yield outwardly as the heel end of the shoe is pushed into the clamp.

In order to prevent yielding of the clamping jaws and consequent displacement of the shoe under the force of the attaching operation, means is provided for locking the clamping jaws rigidly against relative movement after the insertion of the work. A back stop 114 is mounted on a lever 116 pivoted at 118 in the head 88 and pivoted at its upper end to a connecting link 120 which, in turn, is yieldingly connected through a spring 122 to a roller cage 124. The cage 124 contains a ball or roller 126 arranged to engage the upper face of the slide 104. Above the roller 126 a cam plate 128 is secured to the head 88 in such a relation to the parts already described that, when the roller cage 124 is drawn forwardly, the roller binds between the cam plate and the slide 104, effectively locking the latter against forward movement. Inasmuch as, through the connections previously described, the slide 104 moves forwardly as the jaws 98 open, the locking of the slide 104 by the roller clutch against forward movement solidly locks the jaws 98 against further separation and holds the work which has been inserted between them rigidly in position. In order to effect automatically the transverse movement of the work clamp, and at the same time to limit the transverse movement of the jack both absolutely and relatively to the work clamp, the jack is provided with a rearwardly extending projection 130 which enters between two stops 132, 134 carried by the slide 78 which moves transversely with the work clamp. The stops 132, 134 are mounted in a guide 136 and by means of a right and left screw 138 may be adjusted simultaneously toward and from each other. When they are adjusted toward each other until the space between them is only sufficient to admit the projection 130, the jack and the clamp move transversely together as a unit. If the stops are separated by a greater distance lost motion occurs between the projection 130 and the stops and, by varying the adjustment of the stops, the final position of the jack relative to the work clamp may be controlled as desired. This is particularly useful in adjusting the jack to lasts in which the cone or pin hole is at one side of the center.

In order to lock the work clamp against lateral movement from the position into which it has been moved by the operative shifting the jack to one side or the other, the following automatic mechanism is provided: A segmental, toothed locking bar 140 is secured upon the rear face of the clamp carriage 58. A rocker shaft 160, journaled

in the slide 42, carries a toothed locking segment 162 adapted to mesh with the teeth upon the bar 140. A pinion 164, formed upon the rocker shaft, meshes with a toothed segment 166 formed upon one end of a lever 170 which is also pivoted at 172 in the slide 42. The other end of the lever 170 is pivotally connected, through a yielding spring pressed plunger 173, to an adjustable link 174 connected at its opposite end to the walking beam of the heelng machine. After the parts of the work have been properly positioned relatively to each other and the operative has stepped upon the treadle of the machine, the walking beam descends to press the parts of the work into engagement with each other. This operation, through the link 174, causes the segment 162 to engage the bar 140, positively locking the latter, and the clamp carriage upon which it is mounted, against lateral movement. The spring pressed plunger 173 acts as a safety device to prevent breakage in the event of the teeth upon the segment 162 and the bar 140 not meshing properly. This contingency, however, is not likely to occur, since the pitch of the teeth is the same as the pitch of the screw 70, so that one revolution of the screw moves the stops 66, 68 the distance of one tooth upon the segment 162. If, now, the clamp carriage is moved against either of the stops 66 or 68, the teeth of the locking device will mesh properly and they are furthermore sharpened somewhat on their edges in order to cause them to go easily into mesh, even though they may not be exactly in register.

The operation of the mechanism heretofore described is as follows: The jack being swung into its outer position, as indicated in Fig. 2, a heel is placed in the heel holder and a shoe, upon its last, is placed upon the jack and pushed back into the clamp. The clamping jaws yield outwardly to permit the insertion of the shoe and are locked against relative separating movement when the shoe engages the back stop 114 and throws the roller clutch into operation. The jack is moved to the right or the left, as the case may be, until the projection 130 comes into engagement with its limiting stop, which is adjusted to locate the jack properly relatively to the last in the shoe held in the clamp. The jack and clamp are then moved farther in the same direction until the projection 64, upon the rear face of the clamp carrier 58, engages its limiting stop, which is adjusted until the shoe occupies the proper transverse relation to the heel. The treadle is now actuated and pressure is put upon the work. The locking segment 162 automatically meshes with the bar 140, holding the clamp rigidly against movement, and the plate 34 meshes with the plate 38, holding

the jack solidly against transverse movement. The parts of the work are now held firmly stationary in their proper relative positions, all the work holding elements being positively locked, and no relative movement of the parts of the work being possible under the pressure applied to them. The parts all remain in this condition until the operation upon the work, in this instance, 10 the attaching of the heel to the shoe is completed. Now, upon the release of the pressure, the parts return to their normal positions, the jack and work clamp being, as before, freely movable transversely to permit 15 the parts of the next piece of work to be located as desired relatively to each other. The limiting stops for the work clamp and the jack are made simultaneously adjustable equally and oppositely in order automatically 20 to provide for right and left shoes which are ordinarily symmetrical relatively to each other.

Having described the invention, what is claimed as new and desired to be secured by 25 Letters Patent of the United States is:—

1. In a machine of the class described, the combination of a shoe holding clamp normally freely movable transversely of the shoe, and means for automatically locking the clamp against movement at a predetermined period in the operation of the machine.
2. In a machine of the class described, the combination of a shoe holding clamp normally 35 freely movable transversely of the shoe, and means for automatically locking the clamp against movement when the machine is started.
3. In a machine of the class described, the combination of a shoe support, a work holding clamp movable relatively to the shoe support transversely of the shoe, connections between the shoe support and the clamp whereby the movement of the clamp 45 is controlled by the shoe support, and automatic means for locking the clamp against movement.
4. In a machine of the class described, the combination of a shoe support normally 50 freely movable transversely in a right line,

and means for locking the support against movement at a predetermined period in the operation of the machine.

5. In a machine of the class described, the combination of a shoe support and a work holding clamp both normally freely movable transversely of the shoe, and means for locking both the support and the clamp against movement at a predetermined period in the operation of the machine.

6. In a machine of the class described, the combination of a shoe clamp movable transversely of the shoe, stops for limiting the movement of the clamp, a transversely movable shoe support, and a stop, movable with the clamp, for limiting the movement of the shoe support.

7. In a machine of the class described, the combination of a shoe clamp movable transversely of the shoe, adjustable stops for limiting the movement of the clamp, a transversely movable shoe support, a stop, movable with the clamp, for limiting the movement of the shoe support, and means for automatically locking the clamp in the position to which it is moved.

8. In a machine of the class described, the combination of a shoe clamp movable transversely of the shoe, adjustable stops for limiting the movement of the clamp, a movable shoe support, and adjustable stops, movable with the clamp, for determining the limits of movement of the shoe support independently of those of the clamp.

9. In a machine of the class described, the combination of a work clamp having yielding jaws for permitting the insertion of work of different sizes, the clamp being freely movable transversely to permit the work to be positioned as desired, a work support freely movable transversely to permit it to be positioned relatively to the work, and means for automatically locking the clamping jaws, the clamp, and the work support against movement, to hold the work rigidly in position while being operated upon.

In testimony whereof I have signed my name to this specification.

JOHN F. STANDISH.
